UNITED STATES PATENT OFFICE.

CHARLES S. BARON, OF TIFFIN, OHIO.

TOP FOR CONTAINERS.

Application filed July 2, 1921. Serial No. 482,048.

To all whom it may concern:

Be it known that I, CHARLES S. BARON, a citizen of the United States of America, and resident of Tiffin, in the county of Seneca, 5 in the State of Ohio, have invented certain new and useful Improvements in Tops for Containers, of which the following is a specification, reference being had to the accompanying drawing.

10 My invention relates to improvements in tops for containers for liquid or granular substances, such, for example as sugar bowls and syrup jugs, respectively, and has for its main object the provision therein of automatic means for opening and closing the discharge opening thereof.

Further specific objects of my invention are found in the particular opening and closing means employed, which are adapted 20 automatically and positively to open the discharge spout of the container when the container is tilted at any angle suitable for the discharge of its contents, and which will automatically close and effectually seal the 25 spout whenever the longitudinal axis of the container assumes a vertical position.

My invention possesses, besides novelty of structure, the novel provision of means by which the opening and closing means is rendered automatic or easily subject to manipulative control at will, and of provision by which the operative mechanism thereof is carried entirely on the outside of the container and out of reach, under ordinary operative conditions, of the sticky contents there of.

What constitutes my invention will be hereinafter specified in detail and succinctly set forth in the appended claims.

40 In the accompanying drawing:

Figure I is a top plan view of one of my container tops, in present preferred form of embodiment.

Figure II is a side elevation of the upper 45 portion of a container broken away, and thereon a separable top like the one shown in Figure I, said top being partly in vertical section, the better to illustrate the opening and closing mechanism therefor, said mechanism being shown in the closed position and the longitudinal axis of the container being in the vertical position.

Figure III is a side elevation of the subject matter of Figures I and II, showing the 55 longitudinal axis of the container inclined from the vertical, and, in consequence of

such inclination, the lid on the top open for the discharge of the contents of the container.

Referring to the numerals on the drawings, 1 indicates the top of a container 2. I prefer to make the top of metal and the container of glass or fictile material, and to unite them separably by any suitable means, represented by screw threads 3 formed in 60 the top and screwing upon corresponding threads formed on the outside of the open upper end of the container 2. Although the construction described is the one preferred, the top and the container may be united by 65 any preferred means other than the threads 3, or they may be made in one piece if preferred.

The top 1 may be of any suitable and preferred shape, in respect particularly to that 75 portion which covers the open end of the container 2. The dome shape illustrated is suitable, but preferential only.

Upon one side of the top 1, I provide a spout 4 which is preferably united to the top 80 1, as by an inturned flange 5 which may be pressed or bent to conform to an aperture provided for it in the top and without the use of solder. The discharge end 6 of the spout 4 is preferably disposed in a plane at 85 right angles to the longitudinal axis of the container 2, in order that the lid-shank 7 provided for opening and closing the discharge end 6 will, when the container is set upon its own bottom, occupy a substantially 90 horizontal position, as shown in Figure II of the drawing. The lid-shank 7 is hinged at one end to the top 1, upon a pintle 8 at a point comparatively remote from the spout 4, the object of such disposition of the pintle 95 8 being to remove the lid from such proximity to the spout 4 as might expose the hinge at 8 to the obstructive presence of the sticky contents of the container.

The lid-shank 7 carries upon its free end 100 a lid 9 to which it is joined, as by an intermediate section 10, in order that both the lid-shank and the lid may, when the lid is closed, occupy parallel planes at right angles to the longitudinal axis of the container. The lid-shank, lid, and intermediate section 10 are preferably made in one piece from sheet metal which is provided, on all sides except the hinged end at 8, with a depending flange 11. Said flange lends stiffness to the composite member, thereby rendering its construction from thin sheet metal 105 110

feasible. It also affords upon the lid 9 an overhanging guard lip 12 for the discharge end 6 of the spout 4.

The lid-shank 7 is hinged to the top preferably by a knuckle formed therein to encircle the pintle 8, which is preferably made in the form of a staple having ends 15 bent at right angles to the pintle and which are passed through suitable apertures provided for them, respectively, in the top 1. On the inside of the top 1 the ends of the staple are secured to the top as by riveting, indicated at 16. The form of hinge connection just described is presented by way of example only and may be varied at discretion, if preferred.

Between the spout 4 and the pintle 8, and in alignment with those members, I provide, as a part of a hinge connection, a metallic loop 17 which is secured to the top 1, as by ends 18 that are passed through apertures provided for them in the top 1 and are bent, on the inside of the top 1, to hold the loop 17 in place, as indicated, for example, in Figure II of the drawing. The loop 17 secures in hinged relationship to the top 1, one extremity 19 of a bent lever 20, whose opposite extremity, bent to form an intermediate shoulder 21 disposed in parallel relationship to the extremity 19, terminates in an upstanding post 22.

The post 22 is loosely disposed within a slot 23 longitudinally disposed in the lid-shank 7. When the post 22 is moved towards the spout 4, the effect of such movement, through the coaction of the shoulder 21, will be to actuate the lid-shank 7 upon its hinge 8 away from the spout 4. In its normal position the post 22 is located at the rear end of the slot 23, as shown in Figure I of the drawing, and the members 19, 20, and 21, lie in contact with the outer surface of the top 1, protected and substantially concealed by that portion of the flange 12 which extends along opposite sides of the lid-shank 7.

The respective hinge members 8 and 17 suggest two examples of variation of hinge connection, of which a number of kinds are equally available for the purpose indicated.

The upstanding end of the post 22 preferably carries affixed to it a weighted or ponderable knob 25 whose function is two-fold. By reason of its knob-like shape, the member 25 may be utilized for the manipulative opening and closing of the lid 9, as for the purpose of cleaning the top, including the mechanism thereon. In this connection let it be observed that the disposition of the pintle 8 affords means of ready access to all parts of the mechanism, and that the swing of the lid-shank 7 is limited by the presence of the member 20. The knob 25 also, by reason of its weight, functionates in ready response to the force of

gravity. For example, in the position of the container shown in Figure II, the knob stands at rest upon the upright post 22; but whenever the container is tilted in the direction of the spout 4, as indicated in Figure III, its weight will cause the knob 25 to drop in the direction of the spout 4, and, thereby, through the mechanical cooperation of the shoulder 21 and the lid-shank 7, positively to actuate the lid-shank 7 so as to separate the lid from the discharge end 6 of the spout.

Description of the operation of my device is comprehended in the terms of the foregoing specification.

What I claim is:

1. The combination with a container top provided with a discharge spout, of a lid for the spout hinged to the top, and lid opening and closing mechanism comprising a gravitationally actuated bent lever hinged to the top and operative within a slot provided for it in the lid.

2. The combination with a container top provided with a discharge spout, of a lid for the spout hinged to the top, and lid opening and closing mechanism comprising a gravitationally actuated bent lever hinged to the top and operative within a slot provided for it in the lid, said lever terminating in a post working in said slot and having a ponderable knob on the outer end thereof.

3. The combination with a container top having a discharge spout, of a lid for said spout hinged to said top, and a gravitationally actuated ponderable member operatively associated with said lid for opening and closing the same, said member being located on the outside of the top, and pivotally secured to the exterior thereof.

4. The combination with a container top having a discharge spout, of a lid for said spout hinged to said top, and a gravitationally actuated weighted member operatively associated with said lid for opening and closing the same, said member being pivotally secured to the outside of the top intermediate the spout and the hinged connection of said lid, and located on the outside of said top.

5. The combination with a container top having an outlet opening, of a lid for said opening hinged to the top, and a gravitationally actuated weighted member pivotally connected to the exterior of the top, and having a portion beneath said lid, said member being operatively connected to the lid, and being adapted to open and close the same.

6. The combination with a container top having an outlet opening, of a lid for said opening hinged to the top, and a gravitationally actuated weighted member pivotally connected to the exterior of the top and

having a portion beneath said lid, said member when lifting the lid swinging in a direction opposite to the pivotal movement of the lid, and being adapted to open the 5 same upon tilting of said container.

7. The combination with a container top having a discharge spout, of a lid for said spout, a gravitationally actuated member operatively associated with said lid for 10 opening and closing the same, said member and said lid being pivotally connected to the exterior of said top and located outside thereof.

8. The combination with a container top 15 having an outlet opening, of a lid for said opening hinged to the top, and a gravitationally actuated ponderable member pivotally connected to the exterior of the top

for opening and closing the same, and means operatively connecting the member 20 and the lid permitting movement of said member relative to said lid.

9. The combination with a container having an outlet opening, of a lid for said opening hinged to said container, a substantially L-shaped lever pivoted at one end to said container and extending upwardly 25 through an opening in said lid, and a ponderable head secured to the free end of said lever for opening said lid. 30

In testimony whereof, I have hereunto set my hand in the presence of a subscribing witness.

CHARLES S. BARON.

Witness:

HARRY TAGGART.
